CLAIM

The ornamental design for a tire tread and buttress, as shown and described.

DESCRIPTION

FIG. 1 is a perspective view of a tire tread and buttress showing our new design it being understood that the pattern is repeated uniformly throughout the circumference of the tread and buttress and the opposite side is the same as the side shown;

FIG. 2 is a front elevation view thereof; and,
FIG. 3 is a fragmentary side elevational view thereof.
The broken line showing of environmental structure in
FIGS. 1 and 3 of the drawing is for illustrative purposes
only and forms no part of the claimed design.

FIG. 1
